(57) **CLAIM**

The ornamental design for a label holder, as shown and described.

DESCRIPTION

FIG. 1 is a front and bottom perspective view of a first embodiment of the label holder of the invention.

FIG. 2 is a rear and top perspective view thereof.

FIG. 3 is a front and bottom perspective view of a second embodiment of the label holder of the invention.

FIG. 4 is a back and top perspective view of the label holder of FIG. 3.

FIG. 5 is a front and bottom perspective view of a third embodiment of the label holder of the invention.

FIG. 6 is a back and top perspective view of the label holder of FIG. 5.

FIG. 7 is a front and bottom perspective view of a fourth embodiment of the label holder of the invention; and, FIG. 8 is a back and top perspective view of the label holder of FIG. 7.

In all views, the stippling indicates color, but not a particular color.
